C. C. & T. ATTORNEYS.

UNITED STATES PATENT OFFICE.

THEODORUS S. BAILEY, OF BERKELEY, CALIFORNIA.

VESSEL-FILLING APPARATUS.

1,373,935.

Specification of Letters Patent.

Patented Apr. 5, 1921.

Application filed February 14, 1920. Serial No. 358,675.

To all whom it may concern:

Be it known that I, THEODORUS S. BAILEY, a citizen of the United States, residing at Berkeley, in the county of Alameda and State of California, have invented certain new and useful Improvements in Vessel-Filling Apparatus, of which the following is a specification.

The present invention relates to that type of device more particularly illustrated in my Patent No. 1,337,743, granted April 20, 1920, and the particular improvement of the present invention is the provision of means for reception within the troughed body to facilitate the removal of the contents thereof and the retaining of the same within a vessel on the withdrawal of the body from within the vessel.

A further object is to provide a construction which provides a substantial closure for the end or opening of the vessel through which the troughed member is inserted and removed. A still further object is to provide a device for coöperation with the troughed body whereby during one operation thereof the material in the body is shaped to conform or carry out the symmetrical configuration thereof, and during another operation the same assists in depositing the shaped or formed material within the vessel, and at both times protects the hand of the operator from becoming soiled by the material handled.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying drawings, wherein—

Figure 1 is a longitudinal sectional view of a conventional form of grease gun illustrating my invention in operative use in connection therewith.

Fig. 2 is a view in perspective of the preferred embodiment of my invention in use on a filling device.

Fig. 3 is a view in plan of the embodiment of my invention illustrated in Fig. 2.

Referring more particularly to the drawings, wherein like characters of reference designate corresponding parts, 1 indicates the handle and 2 the troughed body of one embodiment of a vessel filling device, as set forth in my Patent No. 1,337,743, granted April 20th, 1920.

To shape the material contained within the troughed body 2 to form the same in a symmetrical configuration as illustrated in dotted lines 3, Fig. 2 of the drawings, I employ a ferrule 4 of an inside diameter corresponding to that of the exterior diameter of the troughed body 2. The ferrule is preferably formed with an annular body 5 and a beveled flange 6 disposed angularly of one end thereof, and from the terminus of the flange 6 extends a handle or displacing member 7, the end 8 of which is preferably formed to correspond with the interior of the troughed body 2, and said handle or displacing member 7 is preferably of a width at least equal to that of the troughed body 2 so that on said handle or displacing member being disposed transversely of the troughed member 2 with its free end 8 seated within the troughed member, the contents of the troughed member in advance of the handle or displacing member 7 will be provided with an abutment by said member 7.

In use it is preferable that the shaping member 4 be positioned on the troughed member 2 adjacent the handle 1, after which time the trough is filled to its capacity with material which projects above the longitudinal side edges of the trough a considerable distance.

When it is desired to shape this material to provide a charge to be inserted into a vessel, it is only necessary to move the shaping member longitudinally of the trough in a direction from the handle 1, which will cause the surplus material to be removed from the material contained in the troughed body 2, and shape the remaining material to carry out the cross configuration of the troughed body 2. This being done, the troughed body with its contained and shaped material is inserted into the vessel 9, illustrated in Fig. 1 as a grease gun, after the plunger 10 thereof has been fully retracted. The operator after shaping the material by withdrawing the shaping member 4 from

the end of the troughed member 2, positions the displacing handle member 7 thereof transversely over the open end of the vessel 9, substantially closing the end thereof, and 5 with its curved or rounded terminal end 8 seated within the base of the channeled member 2 to form the abutment for retaining the material within the vessel 9, withdraws the troughed body 2 from within the 10 vessel causing the material held within the vessel by the displacing handle member 7 to be retained within the vessel due to being held therein when the troughed body member 2 is withdrawn therefrom.

15 It is to be understood that the configuration of the troughed member, shaping member and displacing handle may be constructed in any suitable manner and of any desired number of parts, just so long as the 20 shaping member is capable of forming the material contained within the channeled member above the side edges thereof to conform or carry out the full contour of the troughed member, and the displacing handle member is of such configuration as to be capable of positioning within the troughed member and to close or substantially close 25 the open end of the vessel during the withdrawal of the troughed member therefrom.

30 By reference to Figs. 2 and 3 it will be observed that the shaping and displacing member is preferably formed from a single piece of material such as a flat plate having an enlarged portion at one end which is perforated preferably by a drawing action to 35 provide a walled aperture forming the shaping opening.

Having thus described my invention, what I claim as new and desire to protect by Letters Patent is:—

40 1. In combination with an elongated troughed body open at one end for receiving a body of plastic material, a shaping member provided with an edge formed to coöperate with the troughed body and capable of movement longitudinally thereof for shaping the plastic material received therein to substantially complete the symmetrical contour of the troughed body, and a member 45 extended from said shaping member and adapted for disposing transversely of the

troughed body with its free end seated within the troughed body to displace the contents of the trough on the longitudinal movement of the trough or member relatively to each other. 55

2. A shaping and displacing member for the described purpose, the same comprising a member provided with a shaping aperture and a solid displacing member extended 60 therefrom, the free end of which is shaped to substantially conform to the interior configuration of the shaping aperture.

3. A shaping and displacing member for the described purpose, the same comprising 65 a relatively flat plate formed at one end with an enlargement, said enlargement being provided with an aperture extending therethrough and the terminal end of said flat plate conforming substantially to the interior 70 configuration of said aperture.

4. A combined shaping and displacing member for the described purpose, the same comprising a body provided with a walled opening forming a shaping aperture, and a 75 displacing member extending from a portion of the wall of said opening, said member being of a width substantially equal to the diameter of the opening and at its end of a configuration approximately that of 80 said shaping opening.

5. A shaping and displacing member for the described purpose, the same comprising 85 a relatively flat plate formed at one end with an enlargement, said enlargement being provided with an aperture extending therethrough and of an interior diameter approximately equal to the width of said plate, the terminal end of said plate conforming substantially to the interior configuration 90 of said aperture.

6. A shaping and displacing member for the described purpose, the same comprising 95 a member provided with a shaping portion and a solid displacing member extended therefrom, the free end of which is shaped to substantially conform to the interior configuration of the shaping portion.

In testimony whereof I have signed my name to this specification.

THEODORUS S. BAILEY.
